UNITED STATES PATENT OFFICE.

CHARLES LEHMANN, OF PARIS, FRANCE.

IMPROVEMENT IN WATCHES.

Specification forming part of Letters Patent No. 56,683, dated July 24, 1866.

To all whom it may concern:

Be it known that I, CHARLES LEHMANN, of Paris, France, have invented certain new and useful Improvements in Watches with Keys, of which the following is a specification.

My invention has reference to the combination of a key or winding device with a pendant which presents as its peculiarity the employment of a single inflexible rod to operate the mechanism of the minute-wheels and that which winds up the barrel.

For moving the hands there is no accessory stem on the back; it is only necessary to draw the stem of the key which is provided with two superposed grooves, into one of which alternately a spring-catch works, forming a stop. This stop holds the rod or stem in its proper position, when, by rotating it in the proper direction, the watch may be set to the hour—that is to say, the hands may be moved in either direction without interfering at all with the other mechanism.

Upon pushing in the rod or stem to its normal position the watch may then be wound. The mechanism by which this result is accomplished is arranged in a manner analogous to that of a Bréguet key. The hands remain in the meantime in a state of repose.

The arrangement of the mechanism of which I desire to secure the exclusive ownership may be readily understood by examining the drawings annexed to the present application.

Figure 1 represents a face view of the mechanism of the key drawn to a scale of double size, the rod or stem of the key being placed in the position which it must naturally occupy for winding up the mainspring. Fig. 2 is a transverse section made through the line 1 2. Fig. 3 shows a face view, corresponding with Fig. 1, but in which the rod or stem is placed in the proper position to set the watch to the hour—that is to say, to move the hands only.

The main stem of the key *t* (seen separately in Fig. 4) is surmounted with a milled button, *b*, or crown, and carries a hub having two grooves, *g* and *g'*, so that a toothed socket, *c*, which forms a clutch by engaging with a corresponding part, *c'*, which appertains to the driving helix, by means of the endless screw

h gives motion directly to the shaft of the barrel by the intervention of the helical-toothed wheel *d*. The helix *h* and the toothed part *c'* are fixed—that is to say, they have no transfer movement, but are held in position by the branch *e* of the bridge *E*. The spring *r*, of which one end is rigidly attached to the plate, terminates at the other end in a fork to embrace the groove made in the sleeve *c*, which may be displaced by means of the stem *t*. The spring *r'*, which rises parallel to the stem of the key, terminates in a V-shaped projection or catch, *x*, which enters one or the other of the grooves *g* and *g'*, according as the stem or rod is placed in position to wind up the spring or to move the hands.

The end of the rod or stem *t*, which extends through the helix or screw *h*, carries a small pinion, *f*, the teeth of which engage with those of the wheel *i*, which transmits the rotary motion it receives to the other wheels, *j*, *k*, *l*, and *m*, which connect with the mechanism of the wheels to which the hands are attached.

When the rod *t* is in its normal position the sleeve *c*, fixed upon this rod, is always engaged with the part *c'* of the helix *h* by means of the pressure constantly exercised by the spring *r*, as indicated in Fig. 3. By turning the milled button *b* in the direction of the arrow motion is given to the helix *h*, which controls the helical-toothed wheel fixed on the shaft of the barrel, thereby winding up the watch. When it is turned backward the sleeve *c* falls back to escape the teeth of the part *c'*, which produces the effect of the key Bréguet. At the same time, the small pinion *f* being completely disengaged, the minute-wheels cannot suffer any derangement. When, on the contrary, the rod is drawn in such a manner that the stop *x* of the spring *r'* enters the groove *g'*, Fig. 1, the pinion *f* engages with the wheel *i* and the sleeve *c*, sufficiently removed from the part *c'* that the latter cannot receive any movement either to the right or to the left. By turning the button *b* in one direction or the other the watch may be set to the hour with facility, when the stem *t* may be pushed into its former position to disengage the hands.

Various arrangements of keys having been

ready proposed, I desire that it shall be well understood that I do not claim as my property the whole of the mechanism, nor do I claim the single operating rod or stem, broadly, for winding and setting the hands of a watch; but

What I claim as my invention is—
The arrangement of the clutch $c c'$, in combination with the rod or stem t , constructed

as described, and capable of being connected meditately or immediately with the wheel which controls the mainspring and with the minute-wheel of the watch, substantially as herein set forth.

CHAS. LEHMANN.
